RADIO AND VISUAL WARNING DEVICE

William S. Halstead, Purchase, N. Y., assignor, by
mesne assignments, to Farnsworth Research
Corporation, a corporation of Indiana

Application February 8, 1945, Serial No. 576,769

10 Claims. (Cl. 250—13)

1

This invention pertains to a radio signaling device, and more particularly to a device wherein a radiotelephone in combination with visual signaling means is provided.

Further, the invention pertains to a portable device which embraces a combination radiotelephone and electric spotlight or lantern, with the electric spotlight being capable of automatically flashing synchronously with a radio-emitted tone signal so that the device may be used as a radio and visual warning device either on vehicles such as trains or automobiles, or when used by individuals on the ground.

When the equipment is utilized as a safety aid, the operator may initiate operation of the device so that the radio transmitter will automatically emit a pulsing radio signal, and simultaneously flash a red light, which light is energized in synchronism with the pulsing radio signal. By this means, the engineer of a radio-equipped locomotive approaching such a device, either carried by a flagman on the ground or mounted at the rear of a preceding train, will receive the pulsing radio signal, and if the approaching locomotive is within the effective visual signaling range of the spotlight, the engineer will also see the pulsing light signal which will flash in synchronism with the pulsing radio signal.

Further, by means of the device two-way radiotelephone communications may be exchanged between the engineer of the approaching train and the flagman of the preceding train after reception of the warning signal so that detailed intelligence can be conveyed.

In this application of the invention, which is illustrative of one of its uses on railroads as an aid in averting rear-end collisions between trains, the device of the invention may be removably affixed to the last car of a train, with a remote control connection extending to the interior of the train.

In one modification of the invention, a radio wave reflector is affixed to the train and is so disposed that when the radio device is properly disposed in its predetermined operative position on the train, the radio wave reflector, such as a parabolic reflector, will reflect the signals rearwardly with respect to the train so that the engineman of a following train within effective range of the device may receive the pulsing signal from the train ahead and simultaneously see a flashing light if within effective range of the light beam.

The spotlight incorporated in the device also may be operated so that a constant light beam for general illuminating purposes is obtained.

2

One of the features of the invention is that it is adaptable for routine use by workmen who can use the device as an electric lantern, or as a radiotelephone transmitter and receiver, with use being made of the pulsing light and synchronously-emitted tone signal whenever emergencies may require it. Obviously, since the device is portable, it may be used for communications and warning purposes between trains, between crewmen on the ground, or between a train and workmen on the ground. In the latter application, one of the devices of the invention may be secured at the front of a locomotive or other vehicle, the reflector being positioned in such manner that the radio beam is directed ahead of the locomotive, while a second device as described here is disposed on the ground in the vicinity of work crews to warn them of the approach of the train, as well as to warn the engineer of the presence of the work crew by means of signals transmitted by the stationary unit in the vicinity of the work crew.

The device normally may employ a portable transmitter and receiver, with connections being such that when the pulsing unit is to transmit a periodic warning signal, the equipment is automatically transferred from normal "receive" condition to the pulse "transmit" condition, with the equipment reverting to the normal receiving condition between pulses. A transmitter lockout relay may be employed in the receiver circuit so that if a carrier wave signal from another transmitter is received by the device, the transmitter lockout relay will automatically cause the pulsing unit to become ineffective as long as the carrier signal is being received and simultaneously will cause a visual and/or audible calling or warning signal to become operative on the portable device. A loudspeaker is also connected to the receiver so that an aural signal of relatively high audible intensity will be received on the portable device simultaneously with the visual calling signal. In operation, when the portable device is in use, and another transmitter, such as that located on a locomotive or at a control station, goes on the air, the portable device will automatically cease pulsing and a visual calling light and/or an auxiliary audible calling device, such as a bell, on the portable device will become effective to draw the attention of the operator to the signal. Thereafter, the loudspeaker or the earphone of a handset incorporated in the unit will be effective in reproducing any voice communications coming in from the other transmitter. A handset is also utilized so that two-

way communications may conveniently be employed.

It is an object of this invention to provide a radio signaling device wherein a radiotelephone is used in combination with visual signaling or warning means.

A further object of the invention is to provide a portable radiotelephone communications system and combination visual signaling or warning means.

A further object of the invention is to provide a portable device which includes a radio transmitter and receiver, having in combination a pulsing visual signaling indicating means operative in combination with its complementary transmitter.

A further object of the invention is to provide a communications warning system wherein a pulsing radio tone and pulsing visual signal are simultaneously transmitted from one unit, and the pulsing radio tone may be received on a second unit.

A further object of the invention is to provide a communications warning system wherein a pulsing radio tone and pulsing visual signal are simultaneously transmitted from one unit, and the pulsing radio tone may be aurally received on a second unit, with a second aural alarm signal on the second unit, which second alarm may respond to the received carrier wave energy on the second unit, or may be a pulsing signal operating simultaneously with the pulse received in the loudspeaker of the second device.

A further object of the invention is to provide a communications and/or warning system wherein two substantially similar units as set forth herein are employed so that there will be mutual interaction between two or more devices within effective range of each other.

A further object of the invention is to provide a communications and warning system by using a plurality of similar units as set forth herein, wherein said units periodically emit a radio tone signal, with the receiver of the respective units being periodically placed in operation between the pulses of the radio tone, and a lockout relay being employed in each unit to prevent automatic pulsing of the transmitter while a signal is being received from the second unit, said lockout relay also preventing the transmitter from being operative when the carrier signal energy is being received from another cooperating unit.

Further and other objects may be, and may become apparent from a perusal of the disclosure herein. It is not intended that the specific illustrations be used as limitations except as defined by the spirit of the subjoined claims.

In the drawings:

Fig. 1 is an oblique view of one form of a combination spotlight and portable radiotelephone device embodied in the present invention.

Fig. 2 is a side view illustrating a preferred placement of the batteries and radio equipment inside the case shown in Fig. 1.

Fig. 2A is a side view of a modified form of a portion of the equipment shown in Fig. 2.

Fig. 3 is an irregular cross section of the handset reel and associated contacts in relation to the housing.

Fig. 4 is a side elevational view of the reel device incorporated in the equipment of Fig. 1 and designed to take up slack in a handset cord when not in use.

Fig. 5 is a rear elevational view of the handset cord reel illustrated in Fig. 4, with the spring cover-plate removed.

Fig. 6 is a block diagram of the electrical circuits of the combined spotlight and portable radiotelephone device illustrated in Fig. 1, showing automatic radio and visual signaling means with coordinated pulsing device.

Fig. 7 is an illustrative schematic circuit diagram of the combined visual and radio signaling device shown in Fig. 1.

Fig. 8 is a side view of the device embodied in the present invention showing its use at the rear of a train for rear-end warning purposes.

Fig. 9 is a plan view of two railway tracks with trains thereon, illustrating one form of directional radiation pattern established by the warning device of Fig. 8.

Fig. 10 is a block diagram of a radio communications system similar to that illustrated in Fig. 6 and including a lockout relay for suspending automatic warning pulse transmission during periods in which a signal is being received from other stations.

Referring to the drawings, and more particularly to Fig. 1, there is shown an oblique view of one illustrative form of the equipment embodied in the invention in which a metal case 12 is provided to hold a combination radio receiver and transmitter and associated batteries, the placement details of which will be described later. A hinged top cover 15 allows access to the interior of the case and handle 16 is provided for carrying purposes. The louvers 17 give weather protection to a loudspeaker mounted in the case and to be described later. Handset 19 is held in place by spring clip 21 when not in use. Recessed compartments 23 and 24 are provided to house the receiver 19B and microphone 19A of the handset 19 and to hold it in such manner that it will not project by an excessive amount from the case when held in place by the spring clip 21.

An extruded metal cover 26 is fastened to the side of the case as shown, to house a reel employed to automatically take up the slack on the multiple conductor cord 28 when the handset 19 is not in use. A protective cap 29 with a retaining chain 30 covers a telescopic type of radio antenna when the antenna is not in use. A second protective cap 31 held by a retaining chain 32 covers a multi-connection receptacle so that equipment may be connected thereto to provide control means from a remote point. A spotlight 33 projects from the front of case 12 and contains both a clear light bulb and a red light bulb, to be described later.

Three toggle switches 35, 36, and 37 provide necessary switching controls for controlling operation of different sections of the equipment. Toggle switch 35 applies power to a clear spotlight bulb, to be described in Fig. 2. Toggle switch 36 applies power to the radio equipment so that either the receiver or transmitter may be used, as desired by the operator. Toggle switch 37 applies power to an automatic pulsing device to be later described which causes periodic flash operation of the red light bulb in spotlight 33 and at the same time causes the synchronized radio emission of a warning tone signal at periodic intervals, such as one or two seconds, further details of which will be described later. Indents such as 25 on the sides of case 12 provide fastening means in which locking bolts, not illustrated, may be inserted to hold the equipment in a suitable shock-mounted frame on the front or rear of a train or other vehicle, as will be described subsequently.

Fig. 2 shows in outline form the illustrative placement of the various components within case 12. The spotlight 33 as shown includes clear light

bulb 38, and red light bulb 39, disposed in front of a common reflector 41. Handset 19 is shown held in place by the spring clip 21 while loudspeaker 40 is mounted behind the protecting louvers 17. Fig. 2 also shows a press-to-talk switch 50 in the handset 19 which operates a multiple contact relay, to be described later and which is a part of transmitter-receiver unit 51 and serves to transfer the radio circuits from the normal "receive" condition to the "transmit" position, as will be explained in subsequent paragraphs. The handset 19 is indicated as held in place by spring clip 21 with the recessed compartments 23 and 24 housing the receiver 19B and microphone 19A.

Space is provided for the battery unit 46 consisting of A, B, and C batteries. The telescopic antenna 48 is shown in its closed position, the top of the antenna being covered by the protective cap 29. The radio receiver-transmitter 51 is located in the top portion of the case.

The multiple-conductor handset cord 28 is normally wound around the reel 53 thus taking up the slack which would otherwise protrude from the case when handset 19 is clipped in place on the equipment. This reel has associated with it suitable brushes and contact rings, to be described in connection with Figs. 3-5 inclusive, and is accessible for service and inspection by removing the metal cover 26.

Fig. 2A illustrates an optional arrangement of a portion of the unit wherein the handset 19 employs a loudspeaking type of receiver unit 20 which when placed in the position indicated, provides sufficient sound energy to take the place of the loudspeaker 40, Fig. 2. A suitable horn 20', Fig. 2A, extends downward as shown from the receiver unit 20 to the openings in the louvers 17, thereby providing a weatherproof horn-type loudspeaker.

Fig. 3 is an irregular cross-sectional view of the reel device employed to take up the slack of the handset cord. Reel 53 is provided with a moulded center disc 63 into which are imbedded five contact rings such as 65. The terminating end of the handset cord (not shown) passes through the opening 67 of the reel, while the five conductors of the cord are soldered to contact pins such as 68 which connect through the moulded insulated center disc 63 to their respective contact rings such as 65.

A center bushing 70 is moulded into the insulated center piece 63 and rotates with it on fixed shaft 71, said shaft being suitably secured to the extruded metal cover 26 previously described in connection with Figs. 1 and 2. A locktight screw 73 secures the reel 53 to the shaft 71, washer 73A being positioned between the screw-head 73 and the end of shaft 71 to permit free rotation of bushing 70 without loosening screw 73.

A removable cover 69 is attached to the side of the reel to hold in place the coiled spring 74, one end of which is fastened to the shaft 71 by rivet 76, and the other end of spring 74 being fastened to cover 69 by rivet 75.

The contact assembly 88 consists of five spring contacts such as 79 secured to the insulating plate 81 by means of rivets such as 83. An insulated backplate 82 separates the contact assembly 88 so that the rivets such as 83 will not be shorted when the assembly is held in place on metal supporting partition 84 disposed within the case 12 and which separates the reel compartment from the radio and battery space in the case 12, Fig. 2.

Fig. 4 illustrates a side view of the reel 53 in combination with brush or spring contact assem-

bly 88. This view clearly shows that center screw 73 holds the reel 53 on a center shaft 71, with the contact rings such as 65 being moulded into the center section 63 as is also shown in detail in Fig. 3. The brush or spring contact assembly 88 as shown is provided with five spring contacts or brushes such as 79, fastened to an insulating strip 81 by means of rivets such as 83. Projections such as 86 are provided on the spring contact 79 to facilitate their use as soldering terminals for the connecting wires between the handset cord and the radio equipment.

Fig. 5 is a view of the opposite side of the reel 53 as shown in Fig. 3 but with the cover 69 removed and illustrates the use of a coiled spring 74 to cause rewinding of the handset cord previously described. The spring 74 is normally held in position on the shaft 71 by the rivet 76 with a similar rivet 75 normally being used to secure the other end of the spring to an extruded metal cover 69, as is shown in Fig. 3.

Fig. 6 is a block diagram of the electrical circuits of the equipment in which the battery unit 46 connects through switch 35 to clear spotlight bulb 38. Switch 36 connects the battery unit 46 to the transmit-receive switch 96 and to the transmitter receiver unit 51, or component radio receiver section 51A and cooperative radio transmitter section 51B which for reason of clarity in illustrating the block diagram are represented as two separate units but which in actual practice may consist of a single unit with the transfer switch 96 being used in any well-known circuit to change the circuit functions from the normal "receive" operation to the "transmit" operation. For clarity, an antenna 48 is indicated as connected to either the receiver section 51A or the transmitter section 51B. In the case of a transceiver the antenna coupling to the transmitter may be the same as the antenna coupling to the receiver, as shown in Fig. 7, effecting a single antenna connection with both the transmitter and receiver circuits and operable with either as determined by the position of the transmit-receive switch 96, Fig. 6.

The receiver section 51A is provided with a loudspeaker 40 and an earphone 19B, the latter normally being a part of a handset 19 previously described. The transmitter section 51B is provided with a microphone 19A, and a press-to-talk switch 50, both of which may normally be incorporated in the above-mentioned handset 19 as previously described.

Switch 37 connects the battery unit 46 to an automatic pulsing device 106 which may be of any well known construction such as a bi-metal thermostatically controlled switch or other suitable circuit interrupter of alternate "make" and "break" type operated by an electrical motor or spring driven mechanism. The automatic pulsing device 106, periodically and momentarily connects battery unit 46 to red light bulb 39 and concurrently or simultaneously energizes the transmitter 51B through transfer switch 96 and also connects the output circuit of a tone generator 109 to the signal input circuit of the transmitter 51B, thereby affecting the periodic emission of a radio carrier modulated by the tone signal simultaneously with emission of a visual warning signal from red light 39.

Thus, in emergencies, trainmen from a derailed train or the operator of a truck or other vehicle which may have stopped in a traffic lane in such position as to form a traffic hazard, may use the 75 automatic warning device embodied in the pres-

ent invention to repetitively and automatically convey both a visual warning signal of a distinctive characteristic to oncoming traffic and a radio warning signal which may be received in approaching vehicles as a distinctive tone signal whose audible characteristics are such that they may readily be reproduced by a loudspeaker in the vehicle.

The illustrative schematic radio circuit, Fig. 7, consists of a transceiver combination in which the same tubes and many of the same circuit components are used for both receiving and transmitting, as determined by the operation of a transfer switch 96 to change circuit connections. This change from the normal receive to the transmit position is accomplished in the present instance by a multiple-contact transmit-receive relay 96 or other suitable transfer switch as will be described in detail in subsequent paragraphs.

The toggle switch 35 connects the positive terminal 112 of a 6-volt "A" battery to the spotlight bulb 38. The toggle switch 36 is a two-pole switch in which arm 116 connects the 6-volt A battery terminal 112 to the filaments of the radio transceiver vacuum tubes and arm 117 connects the positive terminal 113 of a 90-volt "B" battery to the plate circuits of the vacuum tubes in the radio equipment. Terminal 114 connects the -A and -B to ground so that all battery circuits are completed to a common ground as indicated in the drawing.

The toggle switch 37, is of three-pole construction, through which arm 164 causes application of 6-volts from positive terminal 112 to the pulsing device or interrupter 106 when switch 36 also is closed. Arm 167 of switch 37 closes the ground-return circuit of red light 39. Arm 170 of switch 37 connects the positive terminal 113 to the radio transceiver as will be explained in more detail in subsequent paragraphs.

Movable contact 123 of relay 96 when in the "transmit" position connects to contact 156 thereby connecting the plate circuit of tube 121 to terminal 139 of transformer 138 which in the "transmit" connection serves as a modulation transformer. Terminal 141 of transformer 138 connects to movable contact 144 of relay 96 and makes contact with contact 158 when the relay is in "transmit" position, connecting the positive "B" terminal 113 to the plate of tube 121 through winding 140 of transformer 138. Movable contact 160 of relay 96 in "transmit" position connects with contact 161 and applies "A" battery voltage to microphone 19A through winding 163 of transformer 126. It will be seen that transformer 126 functions as an interstage audio transformer when winding 125 is connected in the "receive" position and serves as a microphone transformer when winding 163 is connected with the microphone 19A in the "transmit" position.

When switch 37 is closed in conjunction with switch 36, the pulsing circuit of the equipment is placed in operation, switch contact 164 connecting the 6-volt battery circuit to the pulsing unit 106, in this instance indicated as a bi-metallic type of intermittent contact switch. The positive terminal 112 of the 6-volt battery circuit connects through the resistor wire 166 to both the winding of relay 96 and the red light 39. The circuit to the winding of relay 96 is then completed to ground, while the circuit to the red light 39 is completed to ground through the arm 167 of switch 37. The purpose of switch arm 167 being to prevent the red light 39 from operating

when the press-to-talk switch 50 on the handset 19 is pressed while making a voice transmission.

The arm 170 on switch 37 when closed connects the positive terminal 113 of the B battery to movable contact 171 of relay 96 and when relay 96 is closed, connects with contact 173, applies plate voltage to the tone generator tube 172.

The audio-frequency output from the tone generator 172 is coupled through capacitor 174 to terminal 175 on the audio driver transformer 131.

The operation of the automatic pulsing unit 106 is such that when both switches 36 and 37 are closed the radio equipment is automatically transferred at regular periodic intervals from the "receive" position to the "transmit" position, with red light 39 being energized during the "transmit" period. During the "receive" period, resistance wire 166 drops the voltage across the relay 96 and the red light 39 so that they do not effectively operate. As the resistance wire 166 heats the bi-metallic contact arm 176, the contacts 177 close, shorting resistance 166 and providing full voltage to operate the relay 96 and the red light 39 for a short interval until the cooling of bi-metallic contact arm again opens contacts 177, causing opening of relay 96 and dimming of light 39 below the threshold of vision. This cycle is repeated at any desired interval, which may be controlled by adjusting the spacing of contacts 177. Other electrical or mechanical means may be provided to intermittently operate the combined light and radio signal, such as any well-known electric or spring-driven device.

The remote control unit 185 consists of another handset unit 19' comprising earphone 19B', microphone 19A' and press-to-talk switch 50', radio control switch 36' and pulse control switch 37' connected to a multi-contact male plug 184, which when in the receptacle 183 place all of the above-mentioned remote units in parallel with the handset 19 and switches 36 and 37 on the transmitter-receiver unit. Therefore, it will be seen that the remote unit 185 may duplicate the performance of handset 19, switch 36 and switch 37 as previously described.

It may be pointed out that the circuit indicated in block diagram Fig. 6 and schematic diagram, Fig. 7, is purely representative and that separate transmitter-receiver units or other combinations of tubes and switching means may readily be employed to obtain satisfactory results.

Fig. 8 shows one manner in which the case 12 may be attached by clamps 192 on a suitable supporting frame 191 at the rear of a train or other vehicle to provide a combination visual-radio warning signal, both of pulsing characteristics, as previously described. A parabolic reflector 194 may be placed at the rear of the unit and positioned so that it is at an effective reflector location with respect to the antenna 48, thereby producing a rearwardly-directed radio beam extending directionally along the light beam from case 12 where such directional radio pattern is desired for rear-end warning purposes.

A multiple conductor cable 196 with a male plug 184, previously described in reference to Fig. 7, connects the case 12 to the remote control 185, Fig. 8, said remote control consisting of a handset 19' and switches 36' and 37', as previously described in connection with Fig. 7.

When the unit is used in the manner indicat-

ed in Figs. 8 and 9, it can operate as a radio transceiver or a combined pulsing red signal light and radio warning device.

Fig. 9 shows a view of a two-track railroad right of way with trains 201 and 202, moving in opposite directions in which the rear car 198 of train 201 is equipped with a combined radio-light unit and parabolic radio reflector as described in Fig. 8. A portion of the approximate radiation pattern is indicated by the dotted line 199, Fig. 9.

Figure 10 illustrates a block diagram somewhat similar to that shown in Fig. 6 but including only the radio and pulsing units to which has been incorporated a transmitter or pulse lockout feature.

In the figure, the receiver 51A and the transmitter 51B are indicated connected to the antenna 48 through an antenna transfer relay 99 although in the case of a transceiver both the receiver 51A and transmitter 51B may consist of a single unit whereby the antenna transfer relay 99 is not required.

The handset 19 is provided with an earphone unit 19B which is connected to the receiver output in conjunction with the loudspeaker 40, a microphone 19A which connects to the transmitter 51B and a press-to-talk switch 50 which controls the operation of the antenna transfer relay 99 and the plate power transfer relay 100. The pulsing unit 106 is controlled by the operation of a pulse control switch 101. When the switch 101 is closed the pulsing unit 106 operates the plate power transfer relay 100 and the antenna transfer relay 99 simultaneously with the tone generator 109, causing the transmitter to send out a tone pulse at intervals, such as every alternate second.

On the alternate second between pulses the equipment is in the receive position.

In addition to the speaker output circuit of the receiver 51A, a second output is provided for the purpose of operating a transmitter lockout relay 102 so that any incoming signal will operate the visual calling signal 105, and/or an auxiliary audible calling device such as a bell 105A also controlled by relay 102 and placed in operation upon closure thereof, thereby providing both visual and aural calling means. A switch 105B is inserted between relay 102 and bell 105A to permit the operator to take the bell out of operation after a call has been received. The transmitter lockout relay 102 also connects to the pulsing unit 106 so that if the pulsing feature is in operation it will be made inoperative by locking it out of the circuit, thereby allowing the reception of any incoming signal.

What I claim as new and desire to secure by Letters Patent of the United States is:

1. As an article of manufacture, a housing and contained therewithin, a battery, a radio transmitter and a radio receiver energized by said battery, loudspeaker means actuated by said receiver, a light source energized by said battery, a pulse generator connected between said battery and said light source and said transmitter respectively so as to pulse the respective outputs thereof, first switching means mounted upon the exterior of said housing for energizing said transmitter and said light source, an antenna fed from said transmitter, a hand set including a microphone connected to modulate said transmitter, and an earphone actuated from said receiver, and second switching means automatically actuated in timed relation to said first switching means

for alternatively connecting said transmitter and said receiver to said antenna.

2. As an article of manufacture, a housing and contained therewithin, a battery, a radio transmitter and a radio receiver energized by said battery, loudspeaker means actuated by said receiver, a light source energized by said battery, a pulse generator connected between said battery and said light source and said transmitter respectively so as to pulse the respective outputs thereof, first switching means mounted upon the exterior of said housing for energizing said transmitter and said light source, an antenna fed from said transmitter, a hand set including a microphone connected to modulate said transmitter and an earphone actuated from said receiver, and second switching means for alternatively connecting said transmitter and said receiver to said antenna.

3. In a combination radio transceiver and light beam signaling device including a radio transmitter, a radio receiver, a light source, and a power source, pulsing means for periodically and synchronously exciting said transmitter and said light source, means for directing the output of said transmitter and said light source predominantly over substantially a single path, switching means for alternatively exciting said transmitter and said receiver, transducer means connected respectively to said transmitter and said receiver, switching means for putting into operation said pulsing means, and an audio tone generator connected between pulsing means and said transmitter, whereby the output of said transmitter is modulated at audio frequency and pulsed.

4. In a signaling system of the class described, the combination which includes, a power source, a pulse generator controlling the output thereof during transmission, a signaling light and a tone generator controlled by said pulse generator, a transmitter fed from said power source and modulated by the pulsed output of said tone generator, means for directing the respective outputs of said light and said transmitter predominantly over substantially a single path, a receiver fed from said power source and switching means for alternatively connecting said transmitter and said receiver respectively to radiate and to receive energy along said path.

5. In a signaling system of the class described, the combination which includes, a radio transmitter, a radio receiver and a calling signal actuated by the output of said receiver, relay means for alternatively exciting said transmitter and said receiver, means for modulating said transmitter, pulsing means for simultaneously causing intermittent excitation of said modulating means and said relay means, and a transmitter lockout relay actuated by the output of said receiver upon reception of a calling signal and connected to said pulsing means so as to suspend the operation of said pulsing means upon the reception of a signal.

6. In an automatic break-in signaling system, the combination which includes, a transmitter, a receiver, an antenna, relay switching means for alternatively connecting said transmitter and said receiver to said antenna, a pulse generator intermittently energizing said transmitter and simultaneously actuating said switching means so as to connect said transmitter to said antenna, and a transmitter lockout relay actuated by the output of said receiver and connected to said pulse generator so as to de-energize said generator upon

the reception of a signal during an interval between transmitted pulses.

7. In an automatic break-in signaling system, the combination which includes, a transmitter, a receiver, an antenna, first relay switching means for alternatively connecting said transmitter and said receiver to said antenna, a power source, second relay switching means for alternatively connecting said power source to said transmitter and said receiver synchronously with the respective connection of said antenna to said transmitter and said receiver, a pulse generator intermittently modulating said transmitter and simultaneously actuating both said switching means so as to connect said transmitter to said antenna, and simultaneously to connect said transmitter to said power source, and a transmitter lockout relay actuated by the output of said receiver and connected to said pulse generator so as to de-energize said generator upon the reception of a signal during an interval between transmitted pulses.

8. In a signaling system of the class described, the combination which includes, an antenna, a radio transmitter, a radio receiver having at least one plate circuit, an antenna transfer relay and a plate power transfer relay, a pulse generator simultaneously actuating both said relays and modulating said transmitter, and a transmitter lockout relay actuated by said receiver and connected to and controlling the operation of said pulse generator, whereby the connection of said receiver to said antenna and the excitation of the plate circuit of said receiver is made during an interval between transmitted pulses, and whereby the reception of a signal during said interval actuates said transmitter lockout relay and causes said pulse generator to cease operation during said reception.

9. As an article of manufacture, a housing, and secured thereto, the following: a battery, a radio transmitter and a radio receiver energized by said battery, a loudspeaker actuated by said receiver, a light source energized by said battery, a pulse generator connected between said battery and said light source and said transmitter respectively so as to pulse the respective outputs of said light source and said transmitter, first switching means controlling the operation of said transmitter and said light source, an antenna fed from

said transmitter, a handset including a microphone connected to modulate said transmitter and an earphone actuated from said receiver, second switching means for alternatively connecting said transmitter and said receiver to said antenna, an extensible flexible multi-conductor cord connecting said handset to the elements within said housing, and means for automatically taking up the slack of said cord.

10. As an article of manufacture, a housing, and secured thereto the following: a battery, a radio transmitter and a radio receiver energized by said battery, a loudspeaker actuated by said receiver, a light source energized by said battery, a pulse generator connected between said battery and said light source and said transmitter respectively so as to pulse the respective outputs thereof, switching means controlling the operation of said transmitter and said light source, an antenna fed from said transmitter, a handset including a microphone connected to modulate said transmitter, and an earphone actuated from said receiver, switching means for alternatively connecting said transmitter and said receiver to said antenna, a second light source, and a switch connecting said second light source directly to said battery.

WILLIAM S. HALSTEAD.
